CLAIM

The ornamental design for a tablet with card reader, as shown and described.

DESCRIPTION

FIG. 1 is a perspective view of a tablet with card reader; FIG. 2 is a right side view of the design of FIG. 1; FIG. 3 is a left side view of the design of FIG. 1; FIG. 4 is a rear view of the design of FIG. 1; FIG. 5 is a front view of the design of FIG. 1; FIG. 6 is a top view of the design of FIG. 1; FIG. 7 is a bottom view of the design of FIG. 1; and, FIG. 8 is a perspective view of the design of FIG. 1 with a dock.

The broken lines in FIG. 8 depict environmental subject matter only and form no part of the claim, while the remaining broken lines in the drawings depict portions of the tablet with card reader that form no part of the claimed design.

1 Claim, 8 Drawing Sheets(56)
